[57] CLAIM

The ornamental design for a front discharge mixer truck, substantially as shown and described.

DESCRIPTION

FIG. 1 is a side elevational view of a front discharge mixer truck embodying my new design it being understood that the opposite side is substantially a mirror image thereof;

FIG. 2 is a top plan view thereof;

FIG. 3 is a front elevational view thereof;

FIG. 4 is a rear elevational view thereof;

FIG. 5 is a fragmentary sectional view thereof taken along line 5—5 in FIG. 1;

FIG. 6 is a side elevational view of a front discharge mixer truck showing a second embodiment of my new design, the difference being in the length thereof and the addition of a pair of rear wheels, it being understood that the opposite side is substantially a mirror image thereof;

FIG. 7 is a front elevational view of FIG. 6; and

FIG. 8 is a rear elevational view of FIG. 6.
